UNITED STATES PATENT OFFICE.

NICHOLAS J. VERRET AND JAMES PALMER, OF NEW PORT, ARKANSAS,
ASSIGNORS TO DOMESTIC GAS MACHINE COMPANY, OF LITTLE ROCK,
ARKANSAS, A CORPORATION OF ARKANSAS.

CARBURETER.

No. 818,207.

Specification of Letters Patent.

Patented April 17, 1906.

Application filed July 31, 1905. Serial No. 272,070.

To all whom it may concern:

Be it known that we, NICHOLAS J. VERRET and JAMES PALMER, citizens of the United States, and residents of Newport, in the county of Jackson and State of Arkansas, have invented certain Improvements in Carbureters, of which the following is a specification.

The primary object of our invention is to provide a carbureter which is especially adapted for the production of a hydrocarbon mixture or gas for household purposes and of such construction as to furnish different grades of gases for various uses, such as cooking, heating, lighting, &c.

A further object of the invention is to provide a carbureter or apparatus for producing gas which shall be simple and compact in its arrangement, automatic and effective in operation, and perfectly safe in use, whereby the said apparatus may be easily operated by an unskilled person and will require little or no attention after being once properly adjusted.

Other objects and advantages of the invention will hereinafter appear, and what we claim as novel in the peculiar construction, arrangement, and combination of parts will be hereinafter more specifically set forth in the appended claims.

In the drawings, Figure 1 is a side elevation of a carbureter or gas-generator constructed in accordance with our invention and arranged for operation. Fig. 2 is a vertical longitudinal sectional view through the tank or generator. Fig. 3 is a detail plan view of the tier of perforated plates and absorbents carried thereby. Fig. 4 is an enlarged detail sectional view through one group of supporting-plates and absorbents carried thereby. Fig. 5 is a sectional view illustrating the manner of connecting the plates and absorbents. Fig. 6 is a view illustrating the means for operating the apparatus. Fig. 7 is a detail view of the valve. Fig. 8 is a detail view of the feed-operating mechanism.

In carrying out our invention we employ in the first place a tank A of any desired shape, preferably cylindrical, as shown, the said tank being closed at its ends and provided with an inclined bottom, as a, which

latter leads to a valved drain-pipe a' for drawing off any excess of fluid which may accumulate in the tank at any time. Within this tank is arranged a tier of perforated plates B, horizontally disposed and arranged in several series—in the present instance in three series (designated as 1, 2, and 3)—the plates of each series being spaced apart and the several series further spaced apart, as shown in the drawings. The lower plate is located a slight distance above the bottom of the tank, and the upper plate of the tier is located a short distance below the top, and all the plates may be supported in the tank in any suitable manner, preferably by means of the vertical connecting-rods b, which rest directly upon the bottom a of the tank. Connecting the plates and supporting them in the tank by means of these rods permits of their ready removal for the purpose of examination, &c.

Upon the perforated plates B are placed cloths C or other suitable absorbent material which will hold the gasoline or other hydrocarbon fluid in suspension, and in order to permit of a free circulation of air through the tank or generator the plates, as well as the absorbent material thereon, are cut away at opposite ends alternately, forming a circuitous passage.

As shown in Figs. 1 and 2, the gasoline or other hydrocarbon fluid is fed to each group of absorbent material independently from an elevated reservoir or tank D, having a main supply-pipe d and branch pipes d', the latter passing into the tank and discharging above the upper plate of each group or series. Each branch pipe is provided with a feed-valve H, which is preferably of the "needle-valve" type, and immediately below each valve is a glass tube I, forming a part of the branch pipe and permitting the discharge from the feed-valve to be readily seen. The feed-valve is provided with a discharge-nipple h, by which the gasoline or hydrocarbon fluid is dropped at the center of the glass tube. The main supply-pipe d is provided immediately below the tank and above the branch pipes with a cut-off valve d², by which the supply of gasoline may be cut off from the generator when the apparatus is not in use. For the purpose of properly and effect-

ively distributing the gasoline to the several cloths C, and thereby produce perfect carburization, the upper plate of each series or group is provided with a raised convex 5 boss b', disposed centrally of the plate and upon the apex of which the gasoline or hydrocarbon is discharged, and to further effect such proper distribution the perforated supporting-plates are shaped as shown. The 10 several plates are supported on the rods in their proper relation by means of the short bends b², and to hold the cloths on the perforated plates said rods may be further bent, as at b³, and being loosely connected may be 15 turned for releasing the cloths for the purpose of renewing them.

Air under pressure is supplied to the lower end of the generator through the air-supply pipe m, and after being charged in its passage 20 over the saturated absorbent material is drawn off through the gas-discharge pipes n, n', and n², located, respectively, above the first, second, and third groups of absorbents. These several discharge-pipes will furnish gas 25 of different grades. The uppermost pipe receiving the more highly charged gas will of course supply the highest grade, which may be used for cooking, heating, lighting, soldering, brazing, &c., while the second grade 30 may be employed for illuminating and other purposes where the highest grade of gas is not required, and the third grade may be used for economical illumination, &c.

In Fig. 6 we have shown the tank A, having the tier of absorbents, as provided with a 35 single feed, which comprises the valve S, which receives the gasoline from the tank by way of the supply-pipe t and discharges through the top of the tank at the center 40 thereof. This valve is operated through the intervention of certain mechanism operated by the air-pump or driving means for the latter. The valve consists of the seat s, having the nozzle s' and the tapered opening s², into 45 which latter seats the tapered end of a rod V, located in the upper part of the valve and projecting through the top thereof. Above the valve-seat is a glass tube s³, which is approximately the same height as the supply- 50 tank and on the same horizontal plane therewith, so as to indicate the height of gasoline in said tank, while below the valve-seat is a glass tube, as s⁴, by which the feeding of the valve may be watched. The valve-rod V is 55 connected by a set-screw v to the intermediate portion of a rod V', pivoted at one end to a bracket v' and at its other end connected by a set-screw v² to the upper end of an operating-rod W, the latter being seated loosely in 60 the socket x of an operating-lever X, the latter being pivoted, as at x', to a suitable support and so that its opposite or free end will be in the path of a weighted lever Y, loosely mounted on the fan-shaft. In the present 65 instance, as shown, the fan-shaft is provided

with a spool over which is a rope z, connected to a weight and by which the fan is operated. The weighted lever Y is beyond the outer end of the spool, and the latter is provided with a pin, as z', by which the lever is turned around 70 or over until it falls by gravity, and in doing so tilts the lever X, which operates the rod W, and the latter being connected to the valve-rod V opens the valve and discharges a certain amount of gasoline into the tank or 75 generator.

It will be understood that by adjusting the rod W through the set-screw v³ the amount of gasoline to be discharged by the valve may be regulated and also that said operating-rod W may be manipulated independent of the automatic operating mechanism by simply lifting said rod, the lower end being loose in the socket.

Having thus described our invention, we 85 claim—

1. In a carbureter or gas-generator, the combination with a closed tank, of horizontally-disposed perforated plates spaced apart and arranged in groups farther spaced apart, 90 said plates being cut away at opposite sides alternately to provide circuitous passages, valved feed-pipes for the hydrocarbon discharging above each group, an air-inlet pipe entering below the tier of absorbents, and independent gas-service pipes let into the tank above each group of absorbents and leading to different points of consumption, substantially as shown and described.

2. In a carbureter or gas-generator, the combination with a closed tank, of horizontally-disposed perforated plates spaced apart and arranged in groups farther spaced apart, said plates being cut away at opposite sides alternately to provide circuitous passages, 95 rods connected to the plates and supporting the same, absorbents placed upon the plates, valved feed-pipes discharging above each group, an air-inlet pipe at one end of the tank, and gas-discharge pipes entering the 100 tank above the groups of absorbents, substantially as shown and described.

3. In a carbureter or gas-generator, the combination with a closed tank, of horizontally-disposed perforated plates spaced apart 105 and arranged in groups farther spaced apart, said plates being cut away at opposite sides alternately to provide circuitous passages, rods connected to the plates and supporting the same, absorbents placed upon the perforated plates, and bends in the supporting rods for holding the absorbents in place; together with valved feed-pipes discharging above each group of absorbents, an air-inlet pipe and gas-discharge pipes, the latter being 110 located above each group of absorbents, substantially as shown and described.

4. In a carbureter or gas-generator, the combination with a closed tank, of horizontally-disposed perforated plates spaced apart 115

and arranged in groups farther spaced apart, said plates being cut away at opposite sides alternately to provide circuitous passages, rods loosely connected to the plates and supporting the same, absorbents placed upon the perforated plates, and bends in the supporting-rods for holding the absorbents in place; together with feed-pipes, needle-valves therein, glass tubes below the needle-valves and forming a part of the feed-pipes, an air-supply pipe and gas-discharge pipes, the latter being located above each group of absorbents, substantially as shown and described.

15. 5. In a carbureter or gas-generator, the combination with the supply-tank, of a tank or generator having a tier of perforated plates and absorbents supported thereon, of a valve discharging through the center of the top of the tank or generator and comprising a vertical glass tube of the same height as the supply-tank and on the same horizontal plane therewith, a rod extending through the center of said glass tube and having a tapered

end adapted to enter the seat of the valve, 25 and a glass tube below said seat of the valve.

6. In a carbureter or gas-generator, the combination with the tank or generator having a tier of perforated plates and absorbents thereon, a feed-valve discharging through 30 the top of the tank, a pivoted lever connected to the valve-rod, a rod connected to said lever, and an operating-lever connected to the rod; together with a driven shaft, a weighted arm loosely mounted thereon, and 35 a pin carried by the driven shaft for turning the weighted arm over so that it may fall by gravity and operate the lever last above mentioned.

In testimony whereof we have signed our 40 names to this specification in the presence of two subscribing witnesses.
